UNITED STATES PATENT OFFICE

JOHN V. TARLETON, OF JACKSON HEIGHTS, NEW YORK, ASSIGNOR TO POND'S EXTRACT COMPANY, OF NEW YORK, N. Y., A CORPORATION OF DELAWARE

DESIGN FOR A BOTTLE CAP OR THE LIKE

Application filed September 22, 1930. Serial No. 37,036. Term of patent 14 years.

To all whom it may concern:

Be it known that I, JOHN V. TARLETON, a citizen of the United States, residing at Jackson Heights, Long Island, in the county of Queens and State of New York, have invented a new, original, and ornamental Design for Bottle Caps or the like, of which the following is a specification, reference being had to the accompanying drawings, forming part thereof.

In the drawings,

I claim:

The ornamental design for a bottle cap or the like, as shown.

JOHN V. TARLETON.
